FIRE EXTINGUISHER FOR AEROPLANES

Sandy Pallotta, Youngstown, Ohio, assignor of seven-twentieths to Vito Manzi and three-twentieths to Angelo Ialung, both of Detroit, Mich.

Application December 7, 1931, Serial No. 579,621

2 Claims. (Cl. 169—2)

This invention relates to fire extinguishing systems for aircraft, particularly aeroplane and has for an object to provide a sprinkler system which will withstand the changing positions of the ship 5 while maneuvering without getting out of order and which will be built into the ship so as to be available instantly at all times for extinguishing fires.

A further object is to provide a novel mounting 10 in which a standard fire extinguisher may be rotatively held so as to be maintained upright during the various longitudinal and lateral angular inclinations of the ship but may be locked by the pilot in inverted position to discharge its contents 15 where needed.

A further object is to provide a sprinkler system in which fusible plugs close the nozzles of the spray pipes so that in the event of a fire occurring near one of the plugs the plug will be 20 melted and permit the contents of the fire extinguisher to play on the flame.

A further object is to provide an extremely simple and inexpensive fire extinguisher system which will require minimum attention of the pilot 25 in an emergency and will be so mounted as not to interfere with the controls, motor, or any movable part of the ship.

With the above and other objects in view the invention consists in certain novel details of construction and combinations of parts hereinafter 30 fully described and claimed it being understood that various modifications may be resorted to within the scope of the appended claims without departing from the spirit or sacrificing any of 35 the advantages of the invention.

In the accompanying drawings forming part of this specification,

Figure 1 is a side elevation of the fire extinguisher in applied position in an aeroplane and 40 shown in dotted lines in operative position.

Figure 2 is a vertical section taken on the line 2—2 of Figure 1 showing the pivotal mounting of the fire extinguisher.

Figure 3 is an enlarged detail section of the 45 flexible pipe coupling and pivot of one side of the fire extinguisher.

Figure 4 is a fragmentary end elevation showing the fire extinguisher locked in operative position,

Figure 5 is a plan view showing the spray pipe system,

Figure 6 is a side elevation of a fire extinguisher of non-cylindrical shape,

Figure 7 is a side elevation of a modified form

of fire extinguisher employing fusible plugs to control the escape of the spray, and

Figure 8 is a fragmentary sectional view of one of the spray nozzles and its fusible plug.

Referring now to the drawings in which like 60 characters of reference designate similar parts in the various views a conventional monoplane is shown comprising a fuselage 10, wings 11, motor 12, these parts being all of the usual construction.

In carrying out the invention I preferably employ a fire extinguisher 13 of the standard type which must be inverted to play on a fire. I preferably provide the cylindrical casing of the fire extinguisher with a band 14 having a socket 15 70 which receives a gudgeon 16, as shown in Figure 2, that is rigidly secured to the side of the fuselage in any suitable manner. A right angular bracket 17 is bolted at 18 and braced as at 19 or otherwise rigidly secured to the side of 75 the fuselage and is provided with a bearing 19 disposed in alignment with the gudgeon 16. A pipe 20 is secured to the side of the fire extinguisher near the top thereof and is directed downwardly along the side of the fire extinguisher 80 and thence laterally to provide a journal 21 which is rotatably received in the bearing 19 and co-acts with the gudgeon 16 in rotatably mounting the fire extinguisher. The band 14 is so disposed on the fire extinguisher that the fire extinguisher will have most of its weight placed 85 below the band so that normally the fire extinguisher is maintained upright in position, the fire extinguisher swinging freely on its pivotal connection with the fuselage just described, during 90 maneuvering of the plane, such as turning the nose downward or upward as will be understood.

In order to lock the fire extinguisher in operative position, that is in inverted position, a substantially U-shaped catch 22 is pivoted at the 95 bright thereof on the bottom of the fire extinguisher, an eye 23 formed of suitable strap metal being employed for this purpose. The catch is of sufficient length to embrace the angular bracket 17, as best shown in Figure 4 and may be rotated by the pilot in the eye 23 by means of a lateral lever 24 which extends along the bottom of the fire extinguisher and terminates in a grip 25 which extends at substantially a right angle to the lever. When in this inverted position, 100 the fire extinguisher will expel its contents through the hereinafter described spray pipe system in the usual manner.

The spray pipe system comprises a pipe 26 which extends along the top of the motor and ter- 110

minates at intervals in lateral spray nozzle 27, the pipe being continued preferably along the rear side of the motor as shown at 28 and also having a spray nozzle 29 which enters the crank case of the motor and the pipe is furthermore provided with an upstanding portion 30 which as best shown in Figure 5 is connected to a transverse length of pipe 31 that extends along the leading edge of the wing and is equipped at intervals with spray nozzle 32. A feed pipe 33 for the pipe system just described connects with the pipe 28 and passes rearwardly therefrom to the fire extinguisher where it is connected to the outlet pipe 20 of the fire extinguisher by means of a flexible pipe coupling 34 which is best shown in detail in Figure 3 in which the discharge end of the pipe 20 carried by the fire extinguisher terminates in a nozzle which is tapered externally as shown at 35 and is received in the tapered bore 36 of a cylindrical fitting 37 having a flange 38 at one end and having the opposite end threaded to receive the feed pipe 33. The discharge pipe 20 of the fire extinguisher is provided near the tapered nozzle with a flange 39 which is received in the offset portion 40 of a ring 41 that is secured to the flange 38 of the fitting by means of an annular series of bolts 42 having helical springs 43 surrounding the bolts and confined under tension against the ring 41 by the nuts 44 on the bolts. A bracket arm 45 is formed integral with the flange 38 of the pipe fitting 37 and is bolted as shown at 46 to the right angular bracket 17. The springs 43 take up wear between the contacting tapered surfaces 35 and 36 and between the side faces of the flange 38 and offset portion 40 of the ring 41 caused by rotary or swinging movement of the discharge pipe 20 imparted thereto by the fire extinguisher 13 pivoting on its mounting as will be understood.

A modified form of the fire extinguisher system is shown in Figures 7 and 8 in which the fire extinguisher 47 is not of the above described type which must be inverted to become operative, but instead is of the standard stationary type which when one of the spray nozzles is opened, becomes active and discharges its contents. The fire extinguisher of this type is preferably provided with perforated lugs 48 to which bolts 49 are passed to rigidly secure the fire extinguisher to the side of the fuselage.

The spray pipe system includes a feed pipe 50 which passes from the bottom of the fire extinguisher forwardly toward the engine where it is provided with lateral branches 51 and 52, the former entering the crank case and the latter being continued forwardly and along the motor, as shown at 53 and terminating in spray pipe 54. An upright branch 55 extends to about the height of the wing and is equipped with spray pipes 56. The spray pipes are all equipped with fusible plugs.

As best shown in Figure 8, each fusible plug comprises a plug 57 of fusible material which is confined by fingers 58 in advance of the corresponding spray pipe 54, the fingers being brazed or otherwise rigidly secured at the rear end to the pipe. A valve 59 is held in a conical seat 60

in the pipe by means of a helical spring 61 which is confined under tension between the plug 67 and the valve and holds the valve seated. A helical spring 62 is confined under tension between the inner face of the valve and a transverse pin 63 carried by the pipe 54.

When sufficient heat is generated the plug 57 melts and releases the tension of the spring 51 whereupon the tension spring 62 dislodges the valve 59 to permit escape of the contents of the fire extinguisher 47 through the spray pipe 54.

While the preferred form of the invention embodies a cylindrical fire extinguisher 13, shown in Figure 1, which must be up-ended to discharge its contents, it is not necessary that the shape of the fire extinguisher be cylindrical, since, as shown in Figure 6, the fire extinguisher 64 may be flared outwardly at the bottom and obviously other shapes may be employed without departing from the spirit of the invention.

From the above description it will be observed that the fire extinguishing system is built into the aeroplane as an integral unit therewith and is placed on the side of the fuselage near the motor so as not to materially disturb the center of gravitation of the ship so that the system may be easily applied to ships now in use as well as ships during manufacture.

It will be pointed out also that the system above described consists of a few simple parts which are inexpensive to manufacture and install and which include such connections in the liquid line as to be not easily disrupted by sudden shocks and jars.

From the above description it is thought that the construction and operation of my invention will be fully understood without further explanation.

What is claimed is:

1. In an aeroplane, a revoluble fire extinguisher, 115 a stationary bracket for mounting the extinguisher on the airplane having a portion disposed transversely to the extinguisher, and a rotary catch on the bottom of the extinguisher having a forked terminal to engage said transverse portion of the bracket for locking the fire extinguisher stationary in inverted position.

2. In an aeroplane, a fire extinguisher, a pivot for connecting the fire extinguisher on one side to the fuselage of the airplane, a bracket secured 125 to the fuselage of the airplane and having one end forming a bearing, a discharge pipe for the fire extinguisher having an end journaled through the bearing on the bracket and having an annular flange, a spray pipe, a coupling engaged 130 with the end of the spray pipe and having a flanged portion rigidly secured to the bracket, the bore of said coupling receiving the extremity of the discharge pipe and the flange thereof fitting against the flange on the discharge pipe, 135 a ring encircling the discharge pipe and having an offset portion fitting around the flange on the pipe, bolts inserted through the margin of the ring and the flange of the coupling, and expansion springs mounted on said bolts and acting on 140 the flanges to maintain a leak-proof joint.

SANDY PALLOTTA.
